W. C. WRIGHT

APPARATUS FOR SUPPLYING HEATED AIR TO CARBURETORS

Filed July 15, 1921

Wayne C. Wright, Inventor

Attorney

H. Woodward

UNITED STATES PATENT OFFICE.

WAYNE C. WRIGHT, OF PORT LAVACA, TEXAS.

APPARATUS FOR SUPPLYING HEATED AIR TO CARBURETORS.

Application filed July 15, 1921. Serial No. 484,961.

To all whom it may concern:

Be it known that I, WAYNE C. WRIGHT, a citizen of the United States, residing at Port Lavaca, in the county of Calhoun and State of Texas, have invented certain new and useful Improvements in Apparatus for Supplying Heated Air to Carburetors, of which the following is a specification.

The invention has for an object to enable 10 the satisfactory vaporization of the fuel of internal combustion engines as at present used, by preheating of the air content of the charge.

I am aware of the fact that many appliances have been evolved with a similar end in view, such, as a cap enclosing cylinder heads and having an inlet and carburetor connections, as well as those including conduit elements associated with the exhaust 20 manifold, and that which includes a deck in the upper part of the motor hood with passages therethrough around the cylinders to a lower chamber therefrom which air is drawn by the fly-wheel fan. In these prior 25 devices, however, while a partial benefit is derived from their use, due allowance has not been made for the very great speeds at which air moves therein, and only a partial heating effect is obtained at best. In one 30 well known car having a four-cylinder engine and a one-inch passage from the carburetor, with the engine operating at the speed at which it is rated, the air required to supply the piston displacement would 35 have to move through the manifold stem at the rate of about 20,000 feet per minute, and even allowing liberally for rarefaction, it must be seen that the gases move at a rate which does not permit the absorption there- 40 by of much heat from heated surfaces over which it may pass in the fraction of a second intervening between its entrance to the carburetor and its leaving the inlet manifold.

While many prior devices have enlarged 45 passages through which the air supply may travel, these enlargements are only incidental to the provision of more heating surfaces, nor do they succeed in giving a cubic 50 capacity to the heating spaces which will

have a proper relation to the rate of absorption of heat by the air. It is in the latter respect that my invention aims to effect a progressive step, and also to provide an extremely simple and cheaply produced means 55 for accomplishing the functions desired. A further objection to many prior devices having similar purposes is that they involve such increased surface friction that a material impairment of engine efficiency results, 60 which it is an object of my invention to overcome.

Additional objects advantages and features of invention are involved in the construction, arrangement and combination of 65 parts as indicated in the following description and accompanying drawings, in which,

Figure 1 is a perspective view of a motor vehicle power plant embodying my invention, with parts broken away for unobstructed observation of essential elements.

Fig. 2 is a longitudinal sectional view of a similar embodiment but upon a different type of motor and vehicle.

Fig. 3 is an elevational view of a motor 75 boat engine having my invention embodied therewith.

Fig. 4 is a cross section thereof on the line 4-4 of Fig. 3.

Fig. 5 is a formal rear view of an engine, 80 showing the relation thereto of the element 19 of Fig. 1.

Fig. 6 is a diagrammatic view of a motor with my invention.

There is illustrated in Figures 1 and 5, 85 a part of a well known type of motor vehicle, including part of the frame 10, the motor 11, a hood 12, which rests upon the familiar dash-board 13 and the radiator 14, while the fan 15 is mounted and belted immediately behind the radiator, and the carburetor 16 is located upon the right hand side of the motor. The motor is provided with the ordinary forms of exhaust and inlet manifolds 17 and 18, the carburetor being mounted upon the lower end of the latter as customary.

The purpose of the invention is to provide a chamber over the motor, closed at all sides except the bottom, ordinarily, and in 100

some cases partly closed at the bottom, substantially as indicated diagrammatically in Fig. 6, from which chamber the carburetor may draw its supply of air. In attaining this end in the present instance, I mount upon the front end of the motor, immediately behind the fan a vertical transverse planiform plate 19 the contour of which is such that the hood 12, may snugly abut 5 against the upper and side edges thereof when the hood is closed. The plate 19 has a horizontal lower edge on a level just below that of the exhaust manifold, or even with the lower part of the water jacket of 10 a water-cooled engine, or the uppermost cylinder flanges of an air cooled engine. In the case of the particular car illustrated in Figs. 1 and 5, there is also provided a small closure plate 20, of a form to close the 15 arched opening 21 under the dash 13, and around the motor to a level with the lower edge of the front plate 19. The hood is preferably formed with no openings above the level mentioned between the plates 19 20 and 20, but is formed with openings 21 of a suitable form before the plate 19 in the upper part of the hood. By this method, when the hood is closed, it serves as part of a chamber 22 of the character desired, into 25 which will ascend the air heated by the motor, or moving thereinto by displacement of air admitted to the carburetor as will be explained.

The carburetor 16 in this instance is of a 30 type which has but one intake passage, and this is fitted with a conduit extension 23 which may be secured thereto in an suitable manner, the conduit having a vertical part which extends well up into the space beneath the hood, stopping short of the top thereof a short distance.

In Figure 2 there is indicated a familiar make of air-cooled motor 25, the hood 26 of which is customarily provided with an 35 air inlet opening 27 at its forward part. In the present instance, I have provided upon the motor at its forward end a transverse partition adapted to fit within the hood when lowered so as to close communication between the opening 27 and the space to the rear over the engine. The air jacket deck ordinarily provided may be dispensed with, or otherwise located and the air circulation through the jackets changed.

In Figures 3 and 4 there is illustrated 40 formally a motor boat engine 30 provided with a carburetor 31 having two intakes 32 and 33 respectively from each of which there are extended upwardly flues 34 and 35 respectively, of proper form, both stopping at the same level thereabove, about at the height of to top of the motor. Over and around the motor there is a case 36, of sheet metal, which maybe hingedly sup-

ported at one end, and set upon a suitable 65 bracket 37 on the crank case of the engine. The case may also be provided with inwardly extending bottom plates 38 along the forward part, by leaving sufficient openings to admit air in sufficient quantities for 70 the purposes contemplated.

With the various arrangements shown a large volume of air may be contained 75 within the hot air chamber which will move with comparatively slow speed there-through, ordinarily (at a speed of 20 miles per hour, three seconds is considered a proper period).

The partial closure of the bottom will prevent cross drafts and may be of advantage both in land and water vehicles, but is especially useful in boats where cross winds and roll of the boat may combine to make the construction desirable.

It is an advantage of the use of my invention that it secures a highly efficient vaporization of fuel superior to the results attained where the mixture is formed first and heated afterward, and has been found by tests to effect a saving of one half or 90 more of the gasoline required to operate a vehicle having the ordinary carburetor and no heating appliance for the air of the charge.

Further, it is thought that it will minimize the access of fuel to the lubricating oil, by passing around the pistons, which is supposed to occur in some instances.

When equipped with my invention, the motor has been found to run smoothly at 100 all speeds without heating excessively, and with a notable absence of carbon deposits on the surfaces of the cylinder and piston.

The device prevents the character of the charge from being affected by whirls, which often disturb the operation of motor cars with ordinary equipment. Thus, an engine will operate well at times when running with the wind, but not so well if headed against it. Cold cross winds have been known to prevent operation of a car, especially when blowing against the side of the car on which the carburetor is located. It also has the advantage that it prevents the carburetor action from being affected materially by changes of season, as much as in the case of ordinary equipment.

What is claimed:

1. In a motor vehicle, a hood structure, a transverse partition element at the rear end of the hood, a transverse forward partition under the hood whereby a chamber is formed, a motor mounted at the bottom of the chamber and with its upper part only included within the chamber space so that air can enter the chamber around the motor, and a charge forming device associated with the motor having air supply means ar-

ranged to inspire at the extreme upper part so as to enclose the upper part only of the 10 of the chamber air heated by and rising from motor, in combination with an intake ex-around the motor.

2. In a device of the character described, 5 an adapter means for converting internal combustion motors into charge heaters, consisting of an air confining member open to the atmosphere at its bottom but otherwise wholly enclosed and attachable to a motor
- so as to enclose the upper part only of the 10 motor, in combination with an intake ex-around the motor.
- In testimony whereof I have affixed my 15 signature.

WAYNE C. WRIGHT.
